UNITED STATES PATENT OFFICE

2,585,227

WINDING APPARATUS

Peter J. Christman, Green Bay, Wis.

Application March 21, 1946, Serial No. 655,921

4 Claims. (Cl. 242—56)

1

This invention relates to a winding apparatus, and more particularly to a non-stop automatic transfer winding apparatus. The present application is filed in place of my abandoned application Serial No. 470,987.

An object of the invention is to provide a mechanism for continuously winding a web of paper on a plurality of successive cores in a completely automatic operation.

Another object of the invention is to provide apparatus for winding a web on a core or mandrel and automatically severing the web and transferring the leading end thereof to another core or mandrel without interrupting the winding operation. Still another object is to provide in a single machine, apparatus for slitting and perforating a web of paper and for automatically severing the web at pre-determined intervals so that the web may be continuously wound on successive cores.

Another object of the invention is to provide means for automatically severing a paper web which is being wound on a mandrel and for urging the leading end of the severed web against another mandrel. Still another object is to provide mechanism for continuously moving a plurality of mandrels and for synchronizing with the movement of the mandrels the severance of the paper web and the bringing of the leading end of the severed web into engagement with a mandrel.

Other features and advantages will appear from the following specification and drawings, in which:

Fig. 1 is a fragmentary transverse sectional view of the apparatus of the invention; Fig. 2 is a similar fragmentary transverse sectional view of the apparatus showing the severing of the paper web while it is being wound upon a mandrel and the application of the leading end of the web to another mandrel; Fig. 3, an elevational view; Fig. 4, an end elevational view, the view being of the end opposite that shown in Fig. 3; and Fig. 5, a broken plan view.

In the embodiment of the invention described herein and as shown more clearly in Figs. 1 and 2, a paper web 10 is passed between a drive roll 11 and a bed roll 12. In passing about the bed roll 12, the web is brought into adjacent relation with a perforating roll 13 and a splitting roll 14 and then passes between the bed roll 12 and another drive roll 15. From the bed roll 12, the paper web passes to and is wound upon one of the cores 16, 17, 18 and 19 mounted respectively on the mandrels 20, 21, 22 and 23. The ap-

2

paratus is designed to provide a continuous winding operation in which the web is automatically transferred from one mandrel to another without interrupting the operation.

The drive roll 11 on the shaft 24 is positively driven and is arranged with the bed roll 12 to frictionally engage the web 10 therebetween. The bed roll 12 is rotatable on the shaft 25.

The bed roll 12 is equipped with longitudinal recesses 26 which are adapted to receive the perforating knives 27 on the roll 13. The roll 13 on the shaft 28 is synchronized in its rotation with the rotation of the bed roll 12 so that perforating blades 27 register with the recesses 26. As the web 10 passes between the rolls 12 and 13, the perforating knives 27 pass through the web to form perforations therein at longitudinally-spaced portions of the web.

The slitting roll 14 on the shaft 29 is also disposed in adjacent relation with the bed roll 12 and is arranged to engage the web 10 on the roll 12. Preferably, the bed roll 12 is equipped with an annular groove or recess 30 for receiving the annular projecting portion of the slitting roll.

The roll 15 on the shaft 31 may be positively driven and may be arranged with the bed roll 12 to frictionally engage the web 10 therebetween. The positively driven rolls 15 and 11 are rotated in the direction shown by the arrows in Fig. 1.

The mandrels 20, 21, 22 and 23 are rotatably mounted on a movable turret 32, which in turn is rotatably supported by the shaft 33. The turret 32 may be arranged for rotation on the shaft 33 so as to move the mandrels carried thereby in the counter-clockwise direction indicated by the arrow in Fig. 1. Any suitable mechanism may be used for rotating the turret. Preferably, the turret is rotated at such a speed that a mandrel 22 in web winding position as shown in Fig. 1, may be moved to the position of the mandrel 23, in Fig. 1, in the time required to wind the web to its full extent on the core on the mandrel. Thus, the core on the mandrel receives the web when the mandrel reaches the web winding position of the mandrel 22, shown in Fig. 1, and by the time the web has been completely wound on the core on the mandrel, the mandrel has reached the position beyond web winding position in which the mandrel 23 is shown in Fig. 1.

An arm 34, which may if desired be mounted on the shaft 25, carries a knife blade 35 and a nozzle 36. The arm 34 is arranged to move toward and away from the web 10 at the portion thereof between the mandrels 22 and 23. The knife blade 35 may be of any suitable or conventional type

adapted to sever the web when brought into engagement therewith. The nozzle 36 is adapted to receive a conduit for delivering fluid under pressure to the nozzle 36. Preferably, a mixture of compressed air and water is passed into the nozzle and emitted therefrom under pressure.

The arm 34 may be actuated by any suitable means so as to bring the knife blade 35 into engagement with the web 10 at the portion thereof between the mandrels 22 and 23 to sever the web 10 when the core 19 on the mandrel 23 has been fully wound with the web. Preferably, the actuating means for the arm 34 is automatically operable and is synchronized with the movement of the turret 32 so that the arm 34 is moved forwardly when the mandrels reach the position shown in Fig. 1.

The fluid, which is supplied to the nozzle 36, is controlled by a suitable valve mechanism so that fluid under pressure is ejected from the nozzle 36 immediately after the web 10 has been severed by the action of the knife 35. The nozzle 36 thus serves to bring the fluid into engagement with one side of the leading end of the severed web, and thus causes the leading end of the severed web to be brought into engagement with the core 18 of the mandrel 22, as seen in Fig. 2. Fluid is ejected under pressure from the nozzle 36 only immediately after the severance of the web 10, the valve mechanism being synchronized so as to operate only at the periodic intervals of the actuation of the arm 34.

When the web 10 has been fully wound on the core 19 on the mandrel 23 and the mandrel 23 reaches the position shown in Fig. 1, the arm 34 is automatically actuated to bring the knife 35 into engagement with the web 10. The knife 35 severs the web 10 at the portion thereof between the mandrels 22 and 23. Immediately upon the severance of the web 10 by the knife 35, the nozzle 36 ejects a stream of fluid under pressure (preferably a mixture of compressed air and water) to force the leading end of the severed web into engagement with the mandrel 22. The mandrel 22, of course, is in engagement with or immediately adjacent the side of the web opposite that which is adjacent the knife blade 35 and nozzle 36.

A complete machine, which supplies the power for the various operations shown in Figs. 1 and 2, is set out more fully in Figs. 3, 4 and 5. In the latter figures, A designates a base or frame for supporting the operating mechanism hereinafter described. A bracket A' provides a support for the roll 40 which carries the paper stock 10.

A main drive shaft 25 is mounted in the frame A and is equipped with a drive wheel 41 to which power may be supplied by belt or by gear mechanism or by any suitable means. The drive shaft 25 carries the bed roll 12, and at the opposite end of the casing is equipped with a gear 42 meshing with the gear 43 on shaft 24, the gear 44 on shaft 26, the gear 45 on shaft 29, and, as shown more clearly in Fig. 4, the pinion 46 on shaft 31. Shaft 31 carries also the pulley drive member 47.

Suitable pulley and belt means are provided for driving the mandrels 20, 21, 22 and 23 on the turret 32. Such belt mechanism is shown more clearly in Fig. 3. A pulley 48 is mounted upon a standard 49 carried by casing A and receives a belt 50 driven by pulley 47.

Pulley 48 is fixed to a rotatable shaft 51 and shaft 51 carries another pulley 52. A belt 53 connects the pulley 52, a pulley 54 carried by shaft 31, and an idler pulley 55 carried by shaft 56.

Shaft 56 is mounted upon an arm 57 pivotally carried upon casing A by shaft 58 and is urged outwardly against belt 53 by an integrally weighted arm 59. The belt 53 is adapted to engage a drum 60 carried by each of the mandrels 20, 21, 22 and 23 and, as shown best in Fig. 3, the belt normally engages two of the drums at one time. By this means, the rotation of each of the separate mandrels, when in contact with the paper web 10, is rotated independently of the turret shaft 33.

Power is supplied to the turret shaft 33 by the following means: The shaft 25 is provided with a worm 61, as indicated in Fig. 3, and the worm 61 meshes with a worm gear 62 carried by a cross shaft 63. The ends of the cross shaft 63 are provided with bevel gears 64 and 65. Bevel gear 64 meshes with gear 65 carried by shaft 66. Shaft 66 extends through the frame members A and at its opposite end carries gear 67. Gear 67 meshes with an intermediate gear 68 carried upon shaft 69 and, in turn, gear 68 meshes with the upper gear 70 carried upon shaft 71. Shaft 71 carries a pinion 72 which meshes with the large gear 73 carried by turret shaft 33.

Power is supplied to the knife 35 and to the fluid discharge member 26 by the following means: The bevel gear 65 carried by the cross shaft 63 meshes with bevel gear 74 mounted on shaft 75. Shaft 75 carries a wheel 76 to which an eccentric member 77 is pivotally mounted by means of pin 78. The eccentrically-mounted member 77 carries a rod 79 which pivotally engages the member 34 carrying knife 35, as shown best in Fig. 3.

Any suitable means for automatically supplying fluid to the nozzle mechanism 26 may be employed. In the illustration given, the nozzles 26 are connected by a manifold pipe 80 secured to the knife arm 34. Communicating with the pipe 80 is a flexible hose 81 which is supported by bracket 82 on casing A. A pipe 83 connects the hose 81 with a valve device 84, as shown more clearly in Fig. 3. The valve device 84 is provided with a plunger 85 adapted to be engaged by a cam 86 carried by the wheel 76. The cam 86 controls the operation of the plunger 85 to release fluid in timed relationship with the action of the knife when cutting the paper web 10, as heretofore described.

An idler roller 87 is carried by shaft 88 and provides a support for the paper web 10.

In operation, the web 10 is drawn between the drive roll 11 and the bed roll 12 and is passed along the perforating roll 13 and slitting roll 14 and then between the drive roll 15 and bed roll 12. In passing the perforating roll 13 and slitting roll 14, the web is perforated and slit. From the drive roll 15, the web continues to pass along the bed roll 12 to the core 19 on the mandrel 23. As the turret 32 is rotated and the mandrels are moved to the web winding position of mandrel 22 and then beyond this position to the position of mandrel 23, the arm 34 is actuated at intervals so as to sever the web 10 at the portion thereof between the mandrels 22 and 23. The severing of the web is immediately followed by the application of fluid pressure to the side of the leading end of the web which is opposite the side adjacent the mandrel 22. In this manner, the web is brought into engagement with the mandrel 22 and is wound thereon. The continued operation of the device brings the mandrels 20 and 21 into web winding position and then beyond this position. The web is continuously and automatically

cally wound upon the cores on successive mandrels, the transfer of the web from one mandrel to another being completely automatic.

Although the invention has been described in connection with a particular embodiment, it will be apparent that modifications and changes may be made without departing from the spirit and scope of the invention.

I claim:

1. Winding apparatus comprising a frame, a plurality of spaced mandrels movably mounted thereon, means for delivering a web to a first mandrel in web-winding position, means for moving said first mandrel beyond web-winding position and simultaneously moving a second mandrel to web-winding position, said second mandrel in web-winding position being disposed immediately adjacent one side of said web, a knife, means for moving said knife to sever said web at a point beyond said second mandrel, a source of liquid, a liquid nozzle, and valve means actuated in timed relation to the severing of said web by said knife for applying fluid from said source and through said nozzle to the leading end of said severed web immediately after the severance thereof to bring said leading end of the web into engagement with said second mandrel.

2. Winding apparatus comprising a frame, a plurality of spaced mandrels movably mounted thereby, means for delivering a web to a first mandrel in web-winding position, means for moving said first mandrel beyond web-winding position and simultaneously moving a second mandrel to web-winding position immediately adjacent one side of the web, means for severing said web at a point between said first and said second mandrels, a spray nozzle, and means actuated immediately after the severing of said web for discharging fluid through said nozzle upon the leading end of said severed web to bring the same into engagement with the mandrel in web-winding position.

3. Winding apparatus comprising a frame, a

plurality of spaced mandrels movably supported thereby, means for delivering a web to a first mandrel in web-winding position, means for moving said first mandrel beyond web-winding position and simultaneously moving a second mandrel to web-winding position immediately adjacent one side of the web, a knife movably mounted for severing said web at a point between said first and second mandrels, a nozzle carried by said knife and connected with a source of liquid under fluid pressure, and valve means operated in sequence to the severing action of said web for discharging fluid to the leading end of said web to secure the same to the mandrel in web-winding position.

4. Winding apparatus comprising a frame, a plurality of spaced mandrels movably supported thereby, means for delivering a web to a first mandrel in web-winding position, means for moving said first mandrel beyond web-winding position and simultaneously moving a second mandrel to web-winding position immediately adjacent one side of the web, a knife pivotally mounted for engagement with the web between said first and second mandrels to sever the same, a nozzle fixed to said knife and movable into an arcuate path over the leading end of said web after the same has been severed, and means for discharging liquid through said nozzle downwardly upon the end of said web to secure the same to the top side of said mandrel.

PETER J. CHRISTMAN.
